UNITED STATES PATENT OFFICE.

ORLANDO J. FOSTER, OF SILVER LAKE, WISCONSIN.

BURGLAR-PROOF EXPRESS-CAR.

SPECIFICATION forming part of Letters Patent No. 599,170, dated February 15, 1898.

Application filed October 12, 1897. Serial No. 654,964. (No model.)

To all whom it may concern:

Be it known that I, ORLANDO J. FOSTER, of Silver Lake, in the county of Kenosha and State of Wisconsin, have invented a new and 5 useful Improvement in Burglar-Proof Express-Cars, of which the following is a full, clear, and exact description.

The invention relates to an improvement in the arrangement of cars, especially express-cars, and has for its object to so construct a car that it may be effectually defended by a single person and wherein a person entering the car may be held a prisoner outside of the compartment wherein the valuables are contained at the will of the defender of said compartment.

Another object of the invention is to provide a means of communication between the compartments, so that when desirable a person may pass from one compartment to the other only at the will of the occupant of one of the compartments and without the possibility of a second person also gaining access when following the person intentionally admitted.

A further object of the invention is to so construct the said means of communication between the compartments that it may be used as effectually in banks or other structures in which valuables are kept as in an express-car.

The invention consists in the novel construction and combination of the several parts, as will be hereinafter fully set forth, 35 and pointed out in the claims.

Reference is to be had to the accompanying drawings, forming a part of this specification, in which similar characters of reference indicate corresponding parts in all the figures.

Figure 1 is a vertical longitudinal section through a car having the improvement applied. Fig. 2 is a horizontal section taken practically on the line 2 2 of Fig. 1. Fig. 3 is a transverse section through the express-room of an express-car or the room where the valuables are kept and carried. Fig. 4 is an elevation of the blind end of the car. Fig. 5 is a transverse section through a portion of the car, drawn upon an enlarged scale, the 50 section being taken at one side of the partition between the compartments of the car, illustrating the improved door, a portion of

the door being in section. Fig. 6 is an inner face view of the door leading out from the express-compartment of the car, at the side 55 thereof. Fig. 7 is a vertical section through the door shown in Fig. 6. Fig. 8 is a transverse section taken substantially on the line 8 8 of Fig. 5. Fig. 9 is a detail view illustrating a latch applied to a movable partition 60 located in the compartment of the car which is entered at the end of said car. Fig. 10 is a front elevation of a portion of the main partition of the car, illustrating the construction of the peep-holes or ports contained therein. 65 Fig. 11 is a vertical section through the port-holes shown in Fig. 10. Fig. 12 is a horizontal section through the improved door, showing two sections of the door faced in opposite directions to inclose a person. Fig. 13 is a 70 transverse section through the improved door, illustrating the sections as brought one within the other and in position to admit of a person stepping into the desired compartment; and Fig. 14 is a section similar to that shown 75 in Figs. 12 and 13, illustrating the members of the door as placed in position to admit of a free passage-way between adjoining compartments.

The car is divided by a partition 10 into 80 two compartments A and B. The compartment B is that in which the valuables are to be contained, and the only door opening into this compartment is that which is placed in the said partition 10 and is of peculiar construction, the entrance to the car being obtained through a door in the outer end of the compartment A, which is in the nature of a vestibule, but which may be used for the storage of non-valuable articles, if desired. 90

The partition 10 is provided with one or more, usually two, openings 11, placed one at each side of the center at a suitable distance from the floor of the car. In each opening 11 a frame 12 is mounted to rock in a vertical direction, being provided with pinions 13, as shown in Fig. 10, and within each frame 12 a second frame 14 is pivoted, the inner frame 14 being capable of lateral movement. The two frames afford sight-openings, whereby a person in the storage or express compartment B of the car may view the entrance-compartment A from all sides and whereby also a gun or pistol may be passed through a

suitable opening in the inner frame 14 and made to command any portion of the said entrance-compartment. The trunnions 15 of the inner frame 14 are located at top and bottom thereof and are mounted to turn in the outer frame 12, as is clearly shown in Figs. 10 and 11.

In the side walls of the storage or express compartment B turrets C are formed, which are in the nature of bay windows or structures, and the bottoms of the turrets are a predetermined distance from the floor, while the tops of said turrets will extend, preferably, beyond the clear story of the car. The bottom 16 of each turret is preferably made to extend beyond the inner face of the side wall of the car, so as to afford ample room for one or more persons to stand thereon. Sight-openings 17 are made in the bottom portions 20 of the turrets, and similar openings 18 are preferably produced in the upper portions of the turrets, so that persons standing on the floor of the car may see through the lower openings or pass a weapon out through the same, while persons standing on the platforms 16 of the turrets may have a view over the top of the entire train and may pass weapons out through the upper openings of said turrets.

Ordinarily in each side of the express or storage compartment B a door D is located. These doors are usually hinged doors, as illustrated. One of the doors is shown in enlarged view and in detail in Figs. 6 and 7, in which it will be observed that the door is provided 35 at the top, bottom, and at each side with a recess, the recesses communicating. A bolt 19 has vertical movement in the upper recess of the door, a corresponding bolt 21 having vertical movement in the lower recess of the door, while in the side recesses of said door bolts 20 have lateral movement. These bolts are beveled at their ends, so that when they are wholly withdrawn from the recesses in which they are placed they will connect at 45 their opposing ends and their outer faces will be flush with the marginal edges of the door. The bolts are adapted to enter the continuous recess 22 made in that portion of the door-jamb against which the door is to close, and 50 when the bolts of the door are forced outward into the recess 22 in the jamb it will be almost impossible to open the door without tearing down the sides of the car.

The bolts may be operated in various ways; 55 but preferably at or about the central portion of the door four shafts 24, 25, 26, and 27 are placed, extending from the inner face of the door, within the same, and entering recesses or cavities 29, formed at the outer end of the 60 opening, through which the said shafts pass, as shown in Fig. 7. At the outer end of each shaft, within the recess or cavity 29 at that point, an arm 28 is secured, and the arms are connected, through the medium of pins and 65 links 30, with the bolts 19, 20, and 21, to which the shafts belong. Each shaft 24, 25, 26, and 27 is usually provided with a handle 31 at its

inner end in order that the bolts may be expeditiously and conveniently manipulated.

In the central portion of the main partition 70 10 of the car a vertical opening 32 is made. This opening is adapted to receive a door E. The door, as heretofore stated, is of peculiar construction, comprising an outer pivoted semicylindrical section 33 and a corresponding 75 section 34 of less dimensions than the outer semicylindrical section, as illustrated particularly in Fig. 5 and likewise shown in Figs. 12, 13, and 14. The outer section 33 of the door is provided with a tubular projection 80 35 at the top, journaled in a suitable recess in the upper portion of the door-opening, and the inner section of the door is provided with a stud 36, secured to the top of the said inner section and held to turn in the tubular projection 35 of the outer section of the door. The sections of the door extend downward through an opening 37 in the bottom of the car and into a well 38, formed below the said bottom, as shown in Figs. 1 and 5. Upon the 85 bottom of the well 39, which is stationary, a boss 40 is formed at the center having grooves in which balls or rollers 41 may travel. A stud or a post 50 is carried upward from the central portion of the boss 40, terminating at 90 the top in a platform 51. This platform is of such dimensions that it may be contained in the bottom portion of the inner section 34 of the door. The stud 50 extends upward through a collar 52, which is attached to the 100 central portion of the bottom of the inner door-section 34, the said collar terminating at its lower end in a flange 53, provided with grooves to receive the balls or rollers 41, above referred to. At the lower end of the outer 105 section 33 of the door a collar 54 is formed, the said collar having grooves in its under face and the flange 53 having corresponding grooves in its upper face to receive the balls or rollers 55, whereby the sections of the door 110 have roller-bearings upon their supports.

The collar 54 of the outer section of the door is provided with peripheral teeth 56, making the said collar virtually a pinion fixed to the outer section of the door, and the flange 53 of the inner section of the door is likewise converted into a pinion by forming teeth 57 on its periphery.

The teeth of a rack-bar 60, contained within the well 38, engage with the teeth 56 on the 120 collar 54, while a lower and similarly-toothed or rack bar 61 engages with the teeth 57 on the flange 53. The upper rack-bar 60 is attached to the lower end of a lever 63, and the lower rack-bar 61 is attached to a lever 125 62, both of which levers may be pivoted above the car-floor by the same pivot-pin, as shown in Fig. 3, but they normally stand inclined in opposite directions. Each lever is provided with the usual thumb-latch and a keeper 64 130 to be engaged by the thumb-latch of the lever.

Within the entrance-compartment A, at each side near the top, a horizontal guide-rod 65 is secured, the forward ends of the guide-

rods being downwardly curved and extended to the floor, forming uprights 66. A gate F is adapted to travel on the guide-rods 65 and upon the uprights 66. This gate is preferably made flexible, and is shown as comprising an upper cross-bar 67, a lower cross-bar 68, and upright bars 69, the upper and lower cross-bars being provided with suitable eyes or openings which will enable the gate to receive and slide upon the upper guide-rods 65 and the uprights 66. The gate may be, and usually is, provided with a latch 70 at one corner of its lower end, which will engage with a suitable keeper when the gate is forced downward along the uprights 66 to a perpendicular position.

When the gate is in its perpendicular position, it will divide that portion of the entrance-compartment adjacent to the entrance-door from the doorway in the partition 10. The gate F is adapted to be operated from the express or storage chamber B, in which the valuables are placed, and the said gate may be worked in various ways. As shown, a lever 71 is pivoted in the compartment B, the said lever being attached to a link 72, which link is pivotally connected with a gripping bar or arm 73, pivoted to a suitable support above the center of the space between the upper guide-bars 65, the gripping device or arm 73 being normally in engagement with the upper cross-bar 67 of the gate when the gate is supported by the guide-bars 65, this being the normal position of said gate.

Short partitions 74 are placed in the clear story of the car to extend downward near the guide-bars 65, so that when the gate is on the uprights 66 a person within the compartment formed by the gate, the sides of the car, and the partition 10 cannot find an exit therefrom either through the entrance-door of the car or into the compartment containing the valuables, as is clearly shown in Fig. 1.

At the blind end of the car two fender-boards 75 are preferably pivoted upon a single pin 76, located at or about the central portion of the blind end of said car, as shown in Fig. 4. These fender-boards are held at a decided pitch or downward inclination by engagement with pins or stops 77, shown as located one at each side of the draw-head. The fender-boards have an inclination from their pivot-points in opposite directions and render it almost impossible for a person to climb up the blind end of the car to the top, said fender-boards preventing a person obtaining a footing on the projection usual to cars above the coupling. When these fender-boards 75 are not required, they may be carried to the upper position shown in dotted lines in Fig. 4 and made to bear upon pivoted supports 78.

In the operation of the door when the two semicylindrical sections of said door are one within the other and both almost entirely contained within the express-compartment communication between the express-compartment

and entrance-compartment will be completely cut off. In the event a person approaches the express-compartment B the attendant in such compartment by looking through the sight-openings provided in the partition 10 can determine whether or not the person approaching is to be admitted. If so, the person desiring admittance to the express-compartment will step upon the platform 51, and the attendant in the express-compartment by manipulating the lever 63 will cause the outer section of the door to occupy a position the reverse of its initial position, bringing the said section of the door almost entirely within the entrance-compartment of the car, as shown in Fig. 12. The person desiring admittance will at this time be within a cage the walls of which will be the opposing sections of the door. The attendant in the express-compartment will next manipulate the lever 62, which will cause the inner section of the door to be brought within and concentric to the outer section, as shown in Fig. 13, leaving the person on the platform 51 at freedom to step within the express-compartment, but effectually preventing any one else from gaining an entrance unless the door be again manipulated in the manner above set forth.

If at any time it be desired that communication may be uninterruptedly secured between the two compartments A and B of the car, the two sections of the door are carried to the side of the door-opening, as shown in Fig. 14. Should a person force an attendant on the train to enter the express-car for the purpose of effecting an entrance into the compartment where valuables are contained, the attendant in the express-compartment by the aid of the sight-openings may note the number of persons entering said car and their character. The gate F is now in its upper or normal position. The train-hand or other person forced into the car will then step on the platform 51 of the door; but as soon as the person (or persons) accompanying the train-hand approaches the door in the partition 10 the attendant in the express-compartment may operate the lever 71 and cause the gate F to fall to the vertical position, making prisoners of the trespassing parties, and almost at the same time the attendant in the express-compartment can manipulate the lever 63 to bring the train-hand between the two sections of the door, thus shielding him prior to admitting him into the said express-compartment to assist in defending the same.

It is evident that the sectional revolute door may be as effectually used in banks or in any other building or structure where it is desirable to prevent the entrance of unwelcome or unauthorized persons into a certain apartment.

Having thus described my invention, I claim as new and desire to secure by Letters Patent—

1. In a structure divided into compartments, a lever located in one compartment,

horizontal slideways located in the opposite compartment near the top, uprights connected with the said horizontal slideways, and a gate capable of sliding on the said guideways and on the said uprights, and means for operating the said gate by the said lever, for the purpose set forth.

2. In a structure divided into compartments, a lever located in one compartment, 10 horizontal guideways located in the opposite compartment near the top, uprights connected with the said horizontal guideways, and a gate capable of sliding on the said guideways and on the said uprights, a pivoted arm arranged 15 for engagement with the said gate when supported by the said guideways, and a link connection between the said arm and the said lever, whereby the compartment in which the gate is located may be subdivided and the 20 subdivision effected by a person in the adjoining compartment, for the purpose set forth.

3. In a structure divided into compartments, a partition effecting the division, and 25 a revoluble door located in the said partition, the said door being constructed in semicylin-

drical sections, and means for independently operating each section, as specified.

4. In a structure divided into compartments, a partition effecting said division, the 30 said partition being provided with a door-opening, and a sectional revoluble door located in the said opening, and means, substantially as described, for turning the sections of said door upon their axes, for the purpose specified.

5. In a structure divided into compartments, the partition effecting such division being provided with a door-opening, and a door constructed in sections, the sections being mounted to rotate, each section being capable of independent action, a platform located at the bottom of the door-opening, around which the sections of the door turn, shifting-levers, and a rack-and-pinion connection between the shifting-levers and the sections of the said door, for the purpose specified.
